UNITED STATES PATENT OFFICE.

GUY D. McFADDEN, OF PITTSBURGH, PENNSYLVANIA.

DESIGN FOR A LIGHT FIXTURE.

Application filed May 31, 1928. Serial No. 26,922. Term of patent 3½ years.

To all whom it may concern:

Be it known that I, GUY D. McFADDEN, a citizen of the United States of America, and a resident of Pittsburgh, in the county of Allegheny and State of Pennsylvania, have invented a new, original, and ornamental Design for a Light Fixture, of which the following is a specification, reference being had to the accompanying drawing, forming part thereof.

I claim:

The ornamental design for a light fixture, as shown.

GUY D. McFADDEN.
